UNITED STATES PATENT OFFICE.

OSCAR M. LEICH AND ALEXANDER C. REID, OF GENOA, ILLINOIS.

RECEIVER.

1,207,419.

Specification of Letters Patent.

Patented Dec. 5, 1916.

Application filed January 27, 1916. Serial No. 74,699.

To all whom it may concern:

Be it known that we, OSCAR M. LEICH and ALEXANDER C. REID, citizens of the United States, residing at Genoa, in the county of Dekalb and State of Illinois, have invented a certain new and useful Improvement in Receivers, of which the following is a full, clear, concise, and exact description, reference being had to the accompanying drawings, forming a part of this specification.

Our invention relates to head receivers, and has for its object the provision of a new receiver of this type having extreme lightness and providing a new and highly effective distribution of metal for the magnetic circuit thereof.

Our improved receiver has the permanent magnet portion of considerable length in order to insure durability and long life, and also has the permanent magnet constructed in a new way, thus to render it more effective. Furthermore our improved receiver construction permits of a simple removal and replacement of the receiver coil which is a feature of especial interest in receivers of this class as they are usually made within a confined space.

Our invention further contemplates improved structural features among which may be mentioned that the binding terminals which receive the entering cord wires are so constructed that they serve at the same time as distance pieces for the various elements of the receiver structure.

We will explain our invention more in detail by referring to the accompanying drawing illustrating a receiver constructed in accordance with our invention, in which—

Figure 1 is a sectional view of a receiver constructed in accordance with our invention; Fig. 2 is a rear view of the mechanism excluding the shell, cap and diaphragm; Fig. 3 is a front view of the mechanism shown in Fig. 2, portions being broken away more clearly to reveal features of construction, and Fig. 4 is a sectional view similar to Fig. 1 with the shell, cap, diaphragm and cord removed, illustrating the removable coil feature.

The structure as disclosed herein comprises the customary shell 1 coöperating with the cap 2 between whose opposite faces a diaphragm 3 and the protruding annular rim 4 of the internal mechanism are clamped. The internal mechanism which

is shown more clearly in Figs. 2, 3 and 4, omitting the diaphragm, consists of an annular ring 5 having the rim 4 which is held by suitable retaining devices, herein-after explained, in a substantially parallel relation with the permanent magnet consisting of the rings 6 and 7. The rings 6 and 7 are cut-away at 8 to permit the cord 9 to more readily enter the device. The ring 6 has a protruding tongue 9' extending toward the axis of the structure to which is securely fastened a pole piece 10. The permanent magnet structure thus has the greatest length than can be given to it compatible with the interior dimensions of the device. The permanent magnet and the annular ring 5 are in magnetic relation due to the distance piece 11 which is of magnetic material, and which together with said ring and the permanent magnets are held together by the screw 12. The magnetic circuit thus may be said to extend from the finger 9 of the permanent magnet through the pole piece 10 into the diaphragm, from the diaphragm into the ring 5 of magnetic material, from said ring by means of the block 11 back to the point of opposite polarity of the said permanent magnet.

In order further to hold the structure consisting of the two parallel elements 5 and 6, 7, together two binding posts 13 and 14 are provided which are mounted between these two parallel elements, suitable strips of insulation 15 and 16 being provided to prevent them from touching these respective elements. Clamping screws 17 and 18 then extend from the ring 5 to the permanent magnet 6 to hold the structure together, and to clamp the binding posts in position.

As will be clear from Fig. 3, the binding post structures of course have an enlarged ring shaped portion where they encircle the screws 17 and 18 so that these binding posts are not short circuited with the ring 5 as readily apparent. The binding posts furthermore carry screws 19 which clamp the cord tips 20 as these cord tips are passed through holes 21 provided in the cylindrical extremities 22 of said binding post elements. The binding post elements furthermore have protruding fingers 23 which fit in slots provided in the insulating segment 16 so that said binding post elements are prevented from turning and maintain their alinement.

The coil 24 together with the end plates

25 and 26 forms an integral structure as shown more clearly in Fig. 4 which is bodily removable, and which is mounted normally in place upon the stud 10 and held 5 in position by the screw 27. The binding post elements together with the distance piece 11 thus form proper separators for the permanent magnet structure and the ring 5. The binding posts thus serve a dual 10 purpose.

The extreme simplicity of this structure will be readily apparent. The coil of course has its terminals 28 soldered directly to tips 29 protruding from the cylindrical portion 15 22.

From what has been thus described the nature of our invention will be readily clear to those skilled in the art.

Having however thus described one form 20 which our invention may take, what we claim as new and desire to secure by Letters Patent is:

1. A head receiver comprising a ring of magnetic material, a diaphragm circumferentially engaging said ring, a permanent magnet arranged substantially parallel to said ring and backwardly thereof, a centrally located pole piece extending forwardly from said permanent magnet, and a distance piece of magnetic material extending from said ring to said permanent magnet.

2. A head receiver comprising a ring of magnetic material, a diaphragm circumferentially engaging said ring, a permanent magnet arranged substantially parallel to said ring and backwardly thereof, a pole piece extending forwardly from said permanent magnet interiorly of said ring and 40 toward said diaphragm, and a distance piece of magnetic material extending from said ring to said permanent magnet.

3. A head receiver comprising a ring of magnetic material, a diaphragm circumferentially engaging said ring, a permanent magnet arranged substantially parallel to said ring and backwardly thereof, a centrally located pole piece extending forwardly from said permanent magnet, a distance piece of magnetic material extending from said ring to said permanent magnet, an actuating coil encircling said pole piece, and connecting terminals electrically associated with the terminals of said coil mounted 45 between said ring and said permanent magnet.

4. A head receiver comprising a ring of magnetic material, a diaphragm circumferentially engaging said ring, a permanent magnet arranged substantially parallel to said ring and backwardly thereof, a pole piece extending forwardly from said permanent magnet interiorly of said ring and 60 toward said diaphragm, a distance piece of magnetic material extending from said ring

to said permanent magnet, an actuating coil encircling said pole piece, and connecting terminals electrically associated with the terminals of said coil mounted between said ring and said permanent magnet.

5. A head receiver comprising a ring of magnetic material, a diaphragm circumferentially engaging said ring, a permanent magnet arranged substantially parallel to said ring and backwardly thereof, a centrally located pole piece extending forwardly from said permanent magnet, a distance piece of magnetic material extending from said ring to said permanent magnet, an actuating coil encircling said pole piece, connecting terminals electrically associated with the terminals of said coil mounted between said ring and said permanent magnet, and insulating material between said connecting terminals and said ring and said permanent magnet, said connecting terminals serving as distance pieces between said ring and said permanent magnet.

6. A head receiver comprising a ring of magnetic material, a diaphragm circumferentially engaging said ring, a permanent magnet arranged substantially parallel to said ring and backwardly thereof, a pole piece extending forwardly from said permanent magnet interiorly of said ring and 95 toward said diaphragm, a distance piece of magnetic material extending from said ring to said permanent magnet, an actuating coil encircling said pole piece, connecting terminals electrically associated with the terminals of said coil mounted between said ring and said permanent magnet, and insulating material between said connecting terminals and said ring and said permanent magnet, said connecting terminals serving as 100 distance pieces between said ring and said permanent magnet.

7. A head receiver comprising a ring of magnetic material, a diaphragm circumferentially engaging said ring, a permanent 110 magnet arranged substantially parallel to said ring and backwardly thereof, a centrally located pole piece extending forwardly from said permanent magnet, a distance piece of magnetic material extending from said ring to said permanent magnet, an actuating coil encircling said pole piece, connecting terminals electrically associated with the terminals of said coil mounted between said ring and said permanent magnet, 115 insulating material between said connecting terminals and said ring and said permanent magnet, said connecting terminals serving as distance pieces between said ring and said permanent magnet, and means associated with said insulating material for preventing dislocation of said connecting terminals.

8. A head receiver comprising a ring of magnetic material, a diaphragm circumferentially engaging said ring, a permanent 120 magnet,

- magnet arranged substantially parallel to said ring and backwardly thereof, a pole piece extending forwardly from said permanent magnet interiorly of said ring and 5 toward said diaphragm, a distance piece of magnetic material extending from said ring to said permanent magnet, an actuating coil encircling said pole piece, connecting terminals electrically associated with the terminals 10 of said coil mounted between said ring and said permanent magnet, insulating material between said connecting terminals and said ring and said permanent magnet, said connecting terminals serving as distance pieces 15 between said ring and said permanent magnet, and means associated with said insulating material for preventing dislocation of said connecting terminals.
9. A head receiver comprising a ring of magnetic material, a diaphragm circumferentially engaging said ring, a permanent magnet arranged substantially parallel to said ring and backwardly thereof, a centrally located pole piece extending forwardly 20 from said permanent magnet, a distance piece of magnetic material extending from said ring to said permanent magnet, and a self-contained spool of wire removably held in place upon said pole piece.
10. A head receiver comprising a ring of magnetic material, a diaphragm circumferentially engaging said ring, a permanent magnet arranged substantially parallel to said ring and backwardly thereof, a pole 25 piece extending forwardly from said permanent magnet interiorly of said ring and toward said diaphragm, a distance piece of magnetic material extending from said ring to said permanent magnet, and a self-contained spool of wire removably held in place upon said pole piece.
11. A head receiver comprising a ring of magnetic material, a diaphragm circumferentially engaging said ring, a permanent magnet arranged substantially parallel to said ring and backwardly thereof, a centrally located pole piece extending forwardly 30 from said permanent magnet, a distance piece of magnetic material extending from said ring to said permanent magnet, and a self-contained spool of wire removably held in place upon said pole piece.
12. A head receiver comprising a ring of magnetic material, a diaphragm circumferentially engaging said ring, a permanent magnet arranged substantially parallel to said ring and backwardly thereof, a pole piece extending forwardly from said permanent magnet interiorly of said ring and toward said diaphragm, a distance piece of magnetic material extending from said ring to said permanent magnet, a self-contained spool of wire removably held in place upon said pole piece, said spool having one of its ends protruding and a screw adapted to hold said spool removably in position, said screw entering said permanent magnet.
13. A head receiver comprising a ring of magnetic material, a diaphragm circumferentially engaging said ring, a permanent magnet arranged substantially parallel to said ring and backwardly thereof, a centrally located pole piece extending forwardly from said permanent magnet, and a distance piece of magnetic material extending from said ring to said permanent magnet, said permanent magnet consisting of a ring having a radially extending portion, said pole piece extending forwardly from said radial portion.
14. A head receiver comprising a ring of magnetic material, a diaphragm circumferentially engaging said ring, a permanent magnet arranged substantially parallel to said ring and backwardly thereof, a pole piece extending forwardly from said permanent magnet interiorly of said ring and toward said diaphragm, and a distance piece of magnetic material extending from said ring to said permanent magnet, said permanent magnet consisting of a ring having a radially extending portion, said pole piece extending forwardly from said radial portion.
- In witness whereof, we hereunto subscribe our names this 25th day of January, 1916.
- A. D. 1916.
